FIG. 1.

FIG. 2.

Inventor

Tadaso Tsuge

By Joseph W. Harris

Attorney

UNITED STATES PATENT OFFICE

TADAO TSUGE, OF DAIREN CITY, KWANTUNG LEASED TERRITORY, MANCHURIA

PENHOLDER

Application filed October 20, 1928. Serial No. 313,849.

This invention relates to improvements in penholders and similar articles.

An object of my invention is to make a pen-holder graceful and elegant in its appearance and so light in its weight as to make constant writing with it even for many hours at a stretch a tireless task for its user.

A further object is to make an article of the above class, at a low cost, by treating a natural product, Chinese millet, by a simple process.

My invention is illustrated diagrammatically in the accompanying drawings, wherein

Fig. 1 shows the external side view and Fig. 2 shows a view, partly in section, of the penholder.

A stalk of "kaoliang", Chinese millet, is cut into suitable lengths, leaving its skin unpeeled; one end of a cut length is subjected to simultaneous heating and compression to give it a desired shape and increase its density, so that it will firmly and securely hold a metal clamp which latter receives the pen-nib; and also simultaneously heating and compressing the other end of the cut length to give it a gradual tapering shape, or other desired configuration, as in ordinary pen-holders.

In Fig. 1 the stalk of "kaoliang", Chinese millet, is cut into a desired length with its skin A unpeeled. By simultaneously heating and compressing one end the part C is made very firm. At the outward end of this part a metal clamp D, for holding the pen-nib, is thrust longitudinally into the centre B of the stalk. An alternative process is to first have the metal clamp D for the pen-nib forced into the stalk and then to subject the stalk to simultaneous heating and compression so as to make the part C very firm. The two methods are regarded as equivalents for the purposes of this invention. The other end of the stalk is then also simultaneously heated and compressed so as to make it gradually taper at the end E just as in the case with the ordinary pen-holder.

As this invention utilizes, as explained in the above, the stalk of "Kaoliang", Chinese millet, practically in its natural condition 50 to make it into a pen-holder through proc-

esses very much quicker and similar than that ordinarily employed, the cost of production will be much cheaper when compared with that of other pen-holders known hitherto. The skin A of the "kaoliang", 55 Chinese millet, being very strong with its smooth and bright surface, any varnishing or painting may be absolutely dispensed with. The moderate scorching effected at both ends through the heating and the compressing 60 process greatly improves the natural shade of the stalk. Compared with pen-holders made of other kind of material, the penholder manufactured by means of this invention is so much lighter in its weight as to 65 make writing or ruling with it a tireless task even when continued for many hours.

Another merit of the pen-holder manufactured by means of this invention is that the names of parties or articles or the trade 70 marks for an advertisement may be branded upon the skin A of the stalk and such an advertisement is made more effective by its elegance and novelty, especially when it is used as a gift or for the purpose of propaganda.

Having now fully described the details of my invention and in what manner the same is to be performed, I declare that what I claim is:—

1. The method of making pen-holders, which comprises cutting the stalk of "Chinese millet" into suitable lengths, heating and compressing one end of a cut length, thereby shaping and increasing the density of 85 the material at said end, inserting and securing in said end a metal pen-nib retainer, and heating and compressing the other end of said cut length to reduce said other end to a desired configuration. 90

2. A pen-holder comprising a body of "Chinese millet", said body having a pen-nib retainer inserted at one end, the material of the body at said end having increaseable density, and the other end of said body shaped 95 into a desired configuration.

In testimony whereof I affix signature here below.

TADAO TSUGE.
